TIMBER TIE

Joseph J. Veteran, San Jose, Calif.

Application April 14, 1941, Serial No. 388,357

3 Claims. (Cl. 85—14)

The invention relates to a tie element for securing mutually crossed timbers together in contacting relation.

An object of the invention is to provide a tie member which is of relatively simple structure, yet provides a particularly effective tie.

Another object is to provide a tie member of the type described which is automatically tensed in its mounted position by reason of its engagement in the connected timbers.

A further object is to provide a tie member of the character described in which its prongs which engage the connected timbers become anchored therein with a high degree of dependability.

A more specific object is to provide a timber tie which is particularly valuable for the support of one timber from another which immediately overlies it, as the support of a ceiling joist from a "strong-back" beam.

The invention possesses other objects and features of advantage, some of which, with the foregoing, will be set forth or be apparent in the following description of a typical embodiment of the tie, and in the accompanying drawing, in which:

Figure 1 is a perspective view of a tie member embodying the invention.

Figure 2 is a perspective view showing the tie installed and fully operative between two mutually crossed and engaged timbers.

Figures 3 and 4 show the tie member of my invention having its upper prong engaged in a support timber while the lower prong is respectively disengaged and engaged with a timber to be supported from the upper timber.

Figure 5 is a partly sectional view at the line 5—5 in Figure 4.

Figure 6 is an enlarged fragmentary section view taken at the line 6—6 in Figure 5.

Figure 7 is a plan section taken generally at the upper prong of a mounted tie.

As particularly illustrated, the features of present invention are incorporated in the structure of a unitary tie member 9 shaped of a length of material to provide similar terminal prong portions 10 and 11 extending from an intermediate portion 12. The different prongs 10 and 11 extend perpendicularly from the portion 12 and cooperate with said portion to define angularly related planes which are mutually perpendicular in the present instance. Preferably, and as illustrated, the tie member 9 is shaped by bending a length of a bar of rectangular cross-section to have the inside faces of the coterminous sections intersecting in lines perpendicular to their planes. In the present instance, the bar section is square where-

by the different prongs have the same width transversely of said planes.

Means are provided to facilitate the driving of the prongs 10 and 11 into elements to be held together by the members, said means comprising special point and head structures for the prongs. As shown, the free ends of the prongs are provided with wedged-shaped points 13 which terminate at terminal edges appreciably wider than the rectangular bar from which the member is shaped, and the points 13 have their inner faces providing flush continuations of the inner faces 14 of the prongs 11, whereby the points are shaped generally as those of a wood chisel. It will be understood that the wider prong points may be provided by flattening the prong ends thereof.

The bar portions at the junctures of the prongs with the portion 12 are formed with return bends 15 having their outer surfaces providing striking heads 16 in line with the inner prong faces 14 and projecting beyond the rest of the intermediate tie portion 12; in this manner, the force of a driving blow directed against a striking head 16 is operative in a straight line along the inner face 14 of the corresponding prong to the advance edge 17 of the prong point 13. As a prong is driven, it is forced to curve inwardly to provide a hook in the plane it defines with the portion 12, this by reason of the one-way bevel of its point 13 and its rectangular cross-section.

As illustrated, the present tie 9 has been particularly applied for connecting mutually crossed wooden timbers 21 and 22; the upper timber 21 may comprise a strong-back beam from which the timber 22 is suspended by one or more tie members 9 which engage the different timbers at side faces thereof which are mutually perpendicular. It is to be noted, however, that the connected elements may be formed of any structural material which is adapted to have tie prongs driven into it.

In practice, a prong 10 or 11 would first be fully driven into a side face 23 of the supporting timber 21 at a point thereof in line with the face 24 of the timber 22 to be engaged by the other prong and with the point of the second prong 11 or 10 adjacent or resting against the face 24, as is illustrated in Figure 3 wherein the prong 10 is entered in the timber 21 and the prong 11 is disposed for driving into the timber 22. The driving of the prong 11 by striking its head 16 is effected while the timber 22 is manually or otherwise held in place against the timber 21 and, by reason of the chisel-point form of its point 13, results in the curving of the prong 11 as is particularly brought

out in Figure 4. Since the prong 10 is also curved in its place as is shown in Figure 5, the timbers are actually hooked together by the installed tie.

As the second prong, the prong 11, is driven into the timber 22, the intermediate tie portion 12 is swung about the line of the first prong, the prong 10, to twist the latter prong and its widened point in the inner end of the hole made by the point and so further anchor this point in the timber 21, as is indicated in Figure 6. Also, the driving of the second prong has the effect of tensing the intermediate portion 12 between the connected timbers whereby the timbers are positively hooked and held together. For connecting crossed timbers, as in the present showing, tie members 9 may be installed at diagonally opposite sides of the intersection as is brought out in Figures 5 and 7.

Since a prong 10 or 11 may extend transversely in either one of two directions from the plane defined by the intermediate tie portion and the other prong 11 or 10, it will be understood that the present tie members may have either of two forms for use in tying timbers together. Thus, a tie member 9' to engage between the side face 23 of the timber 21 and the other side face 24' of the timber 22 would have its lower prong 11' directed oppositely from its disclosed direction in the tie 9. A tie 9' having the latter form is shown as installed in Figure 4, it being understood that such a tie is the full operative equivalent of a tie 9.

Noting that the material of the tie members is appropriately bendable to permit the described hooked engagement of the prongs in a timber, it is found that the driving of the prongs into place may result in a flattening out and disappearance of the bends 15 which provide the striking heads 16 after the intermediate tie portion 12 has engaged flat against the timber face 24, this being brought out in Figures 4 and 5.

While the present wooden timbers 21 and 22 are shown as engaged in the planes of their opposed edges, it will be readily understood that the described ties are just as applicable for their purposes to members which are notched, and even halved, together. Also, it will be noted that the present ties are equally applicable for tying together laterally engaged timbers, or other nail-receiving elements, which are in T or angle relation, and that the term "crossed" as herein used includes such relations of elements to be mutually secured. Furthermore, if the angularity of the elements to be tied together is different from a right angle, as is shown, for purposes of illustration, a present tie element may be torsionally twisted to dispose its prongs in a corresponding angular relation.

In view of the foregoing description, it will be understood that the present tie members are easy to install, have their prongs self-anchoring in the members into which they are driven, and posi-

tively hook the members together. While the present showing and description are in terms of the application of the tie members for supporting one timber from another, it will be obvious that the present tie members are applicable for securing crossed members generally.

From the foregoing description taken in connection with the accompanying drawing, the advantages of the construction and method of use 10 will be readily understood by those skilled in the art to which the invention appertains. While I have described a device which I now consider to be a preferred embodiment of my invention, I desire to have it understood that the showing is primarily illustrative, and that such changes may be made, when desired, as fall within the scope of the following claims.

I claim:

1. In a unitary member for mutually tieing crossed and engaged timber or other elements, an intermediate section, and terminal prong sections for driving into the different elements extending laterally from said intermediate section and defining with the latter section planes which are angularly related in accordance with the angle of the elements, a prong of a section having a wedge point with the coterminous inner point and prong faces flat and mutually coplanar and having said prong point appreciably wider than the rest of the prong.

2. In a unitary member for mutually tieing crossed timber or other elements, an intermediate section, and terminal prong sections arranged for driving into the different elements and extending laterally from said intermediate section and defining with the latter section planes which are angularly related in accordance with the angle of the elements, a prong of a section being provided with a wedge point appreciably wider than the rest of the prong and having its inner face coplanar with the inner side line of the prong whereby the driving of the prong is arranged to effect a curving thereof toward the intermediate section of the member.

3. In a unitary member for mutually tieing crossed and engaged timber or other elements, an intermediate section, and similar terminal prong sections arranged for driving successively into the different elements and extending laterally from said intermediate section and defining with the latter section planes which are angularly related in accordance with the angle of the elements, the prongs of the sections each being formed with a wedge point having its inner face coplanar with the inner side line of its prong whereby the driving of each prong into an element is arranged to effect an inward curving of the prong and the driven prongs are cooperative through the intermediate section to hook the elements together thereat with said intermediate section in tension.

JOSEPH J. VETERAN.
